CLAIM

The ornamental design for a "dongle", as shown and described.

DESCRIPTION

FIG. 1 is a perspective view of a dongle.

FIG. 2 is a front view of the dongle of FIG. 1.

FIG. 3 is a rear view of the dongle of FIG. 1.

FIG. 4 is a right side view of the dongle of FIG. 1.

FIG. 5 is a left side view of the dongle of FIG. 1.

FIG. 6 is a top view of the dongle of FIG. 1; and,

FIG. 7 is a bottom view of the dongle of FIG. 1.

The features shown in broken lines form no part of the claimed design.

The lighter solid lines denote surfaces and contours. Line shading is not surface ornamentation.
